(57) **CLAIM**

The ornamental design for a hollow rectangular traffic barricade for safety cable connection, as shown and described.

DESCRIPTION

FIG. 1 Shows right front isometric view of with water fill cap on top, an outlet to drain the water, and molded tubes through the body of the barricade which will allow a connection using rope, cable, or a similar material.

FIG. 2 Shows front view of claim 1 thereof;

FIG. 3 Shows top view of claim 1 thereof;

FIG. 4 Shows back view of claim 1 thereof;

FIG. 5 Shows bottom view of claim 1 thereof;

FIG. 6 Shows left side view of claim 1 thereof;

FIG. 7 Shows right side view of claim 1 thereof; and,

FIG. 8 Shows left front isometric view of claim 1 thereof.
